[57] CLAIM

The ornamental design for an in line skating glove, as shown and described.

DESCRIPTION

FIG. 1 is a top perspective view of an in line skating glove showing my new design;

FIG. 2 is a right side elevational view thereof, the left side is a mirror image;

FIG. 3 is a top plan view thereof;

FIG. 4 is a bottom plan view thereof;

FIG. 5 is a front perspective view thereof;

FIG. 6 is a rear perspective view thereof; and,

FIG. 7 is a second embodiment of an in line skating glove showing my new design, the bottom, top, right side, left side, and front are essentially the same as the embodiment of FIG. 1, the difference being the fabric.
